CLOCK RADIO

Jack De Young, Spring Lake, Mich., assignor to Zenith
Radio Corporation, a corporation of Delaware

Application January 24, 1957, Serial No. 44,590

Term of patent 7 years

(Cl. D56—4)

FIG. 1

FIG. 2

FIG. 3

Figure 1 is a front elevational view of a clock radio, showing my new design;

Figure 2 is a side elevational view from the left of Figure 1; and

Figure 3 is a front perspective view thereof, with the grille shown schematically rather than in detail.

I claim:

The ornamental design of a clock radio, substantially as shown and described.
